LIQUID DEFLECTOR MEANS FOR USE IN TUBE SPINNING APPARATUS FOR RAYON AND THE LIKE

Ernest J. Griset, Jr., Asheville, N. C., assignor to American Enka Corporation, Enka, N. C., a corporation of Delaware

Application April 27, 1953, Serial No. 351,234

5 Claims. (Cl. 68—181)

This invention relates to tube spinning and more particularly to those portions of tube spinning apparatus that effect the introduction of a running yarn into a tube and the transfer of yarn from one tube to another.

In the tube spinning art succeeding portions of a yarn are subjected to the action of different treating liquids which not only effect treatment of the yarn but also propel it through the tubes. Consequently, a tube spinning system usually includes a plurality of tubes for serving each spinning position and the problem of transferring the yarn from one tube to the other must be faced.

The transfer problem is really a dual one involving the temporary conditions prevailing only during spinning-in and the more permanent conditions prevailing during all stages of the operation. During spinning-in the yarn and propelling liquid must go together to an introduction zone in which the yarn is introduced into the next tube of the particular series used. Thereafter, to avoid treating liquid intermixing and to facilitate liquid recovery, the yarn is caused to continue to move to the mouth of the next tube while the liquid issuing from the preceding tube is caused to follow a divergent path in relation to the yarn. This act of separating the yarn and the liquid after spinning-in often produces wasteful and troublesome splash.

At all stages of the tube spinning operation each treating tube has a jet of liquid being ejected into its mouth and, when the jet nozzle is spaced from the mouth of the tube being served, alignment is critical in order to insure proper propulsion speeds and the avoidance of splash. While these problems exist in tube spinning generally, it will be appreciated that in the treatment of tow, where a number of yarns are handled simultaneously, the larger volume of liquid being handled is an aggravating circumstance.

It is an object of this invention to provide for the simple and waste free introduction of treating liquid into spinning tubes under conditions which also reduce the splash and waste incident to the separation of treating liquid and yarn paths after spinning-in.

It is a further object of this invention to provide for the introduction of treating liquids into tubes in a manner to avoid nozzle alignment difficulties.

It is proposed, according to this invention to separate the yarn and liquid issuing from a spinning tube in such a manner that any splash incident to this separation is inconsequential.

Other objects and advantages of this invention will be apparent upon consideration of the following detailed description of several embodiments thereof in conjunction with the annexed drawings wherein:

Figure 1 is a view partially in section and partially in elevation of a portion of a tube spinning system showing a liquid introduction arrangement according to the present invention.

Figure 2 is also a view in elevation and vertical section but it also shows a different liquid and yarn transfer deflector arrangement between the exit end of one tube of a series and the mouth of the next tube thereof.

2

Figure 3 is a top plan view of the arrangement of Figure 2 showing the spinning in position of the deflector in full lines and the normal operating position in broken lines;

5 Figure 4 is another view in elevation and vertical section, but, in this view, a liquid introduction arrangement different from that of Figure 1 is shown as well as a deflector arrangement different from Figures 1-3, inclusive;

Figure 5 is a fragmentary view in longitudinal section 10 of the liquid introduction scheme of Figures 1, 2 and 3;

Figure 6 is a similar view of the liquid introduction scheme of Figure 4; and

Figure 7 is a fragmentary view in longitudinal section 15 of a third modification of the liquid introduction arrangement.

It is to be understood that this invention is a continuation-in-part of Griset application Serial No. 122,560, filed October 20, 1949, and that the improvements of this invention relate to but a portion of the spinning system of 20 the parent case. In the parent application it is explained that a yarn to be after treated is introduced into a tube through which it is propelled by a treating liquid and that upon issuing from that tube it is introduced into another until it has progressed through a series of tubes 25 sufficient to accomplish the desired treatment of the yarns.

Figure 1 of the present case shows an end 10 of one 30 treating tube 11 and the mouth 12 of the next tube 13 of the system. Tubes 11 and 13 are supported in a jet box structure 14 which may, and usually does, support other tubes of the system which are not shown in Figure 1. The box 14 is provided with a drain boss 15 registered below the exit end 10 of the tube 11 and with another drain boss 16 registered below the mouth 12 of the tube 13.

Bridging the space between the exit end 10 of the tube 35 11 and the entrance mouth 12 of the tube 13 there is a deflector 17 comprised of a movable upper part 18 and a stationary lower part 19. The two parts 18 and 19 (when the part 18 is in the broken line position of Figure 1) define a groove which serves to guide liquid and yarn 40 issuing from the tube 11 to a point adjacent the mouth 12 of the tube 13. This position is kept until the yarn is running in the tube 13 whereupon the portion 18 of the deflector is moved to the solid line position of Figure 1 so that liquid issuing from the end 10 of the tube 11 flows 45 out of the boss 15 to recovery all in a manner described in Serial No. 122,560, filed October 20, 1949.

The tube 13 is supplied with liquid from a tube 20 provided with a nozzle 21. While in application Serial No. 122,560, mentioned above, there is a nozzle for ejecting liquid into the mouth of the treatment tube, the arrangement of the parent case is one in which the nozzle is spaced away from the mouth of the treating tube rather than being disposed within the treating tube beyond its mouth as is the case in Figure 1. The tubes 11 and 13 of Figure 1 may be tubes of large internal diameter of the type used 50 in the treatment of tow. Thus, the mouth 12 of the tube 13 is so dimensioned as to accommodate entering tow as well as the nozzle 21. The jet of liquid issuing from nozzle 21 creates a negative pressure zone at the mouth 12 of the tube 13 whereby yarn is sucked in. This is also true if the nozzle lies without the treatment tube as shown in Serial 55 No. 122,560. In the arrangement of Figure 1 hereof, however, alignment difficulties inherent in spacing the nozzle away from the mouth of the tube are avoided.

It will be noted that the deflector 17 of Figure 1 has its 60 portion 18 mounted for rotation about a horizontal axis at 22. In rotating about a horizontal axis, it is evident that the channel defining part moves against the stream issuing from the exit end 10 of the tube 11, but it causes little splash during the counter-clockwise shift from the broken 65 line to the full line position because of the short total length of portion 18.

In Figure 2 there is shown a different arrangement in which the deflector rotates about a vertical rather than a horizontal axis. In Figures 2 and 3 parts identical to parts shown in Figure 1 bear like reference numerals and function in the same way. The difference, then, between Figure 1 and Figures 2 and 3 lies entirely in the deflector and the portion of the jet box on which it is mounted. The deflector 23 of Figures 2 and 3 is a unitary structure, but it has about the same shape as the over-all shape of the deflector 17 of Figure 1 when the part 18 is in the broken line position of Figure 1. The deflector 23 includes a channel 24 extending between the end 10 of the tube 11 and the mouth 12 of the tube 13. The bottom of the deflector 23 is provided with a cylindrical cavity into which there projects a pivot pin 25 extending up from or constituting a part of the jet box 26. Since the deflector 23 is mounted on the pin 25 for rotation thereabout, it is evident that once spinning-in is completed, the deflector may be turned at right angles from the full line to the broken line position of Figures 2 and 3 whereby to establish a flow path between the end 10 of the tube 11 and boss 15 of the jet box 26, while permitting the yarn or tow issuing from tube 11 to continue to enter the mouth 12 of the tube 13. In view of the slope of the deflector 23 and the position of the pin 25, it is possible to separate the liquid and yarns issuing from the tube 11 almost instantly by rotating the deflector 23 90° clockwise as viewed in Figure 3 from the full line position to the broken line position. The movement is so quick that any splashing endures for such a short interval of time as to be inconsequential from the point of view of plant operation.

In Figure 4 there is shown another type of deflector which results in splash free operation largely because of the path of its movement. In Figure 4 the jet box bears numeral 27 and the tubes which are illustrated include a treating tube 28, having a discharge end 29 registering with a drain boss 30 and a treating tube 31, having a mouth 32 registering with a drain boss 33. The housing 27 supports a deflector 34 rotatable about a horizontal axis at 35. The deflector 34, in common with the deflectors 17 and 23, defines a channel between the end 29 of one tube and the mouth 32 of the next tube in the series. In Figure 4 the channel bears reference numeral 36. After spinning-in, the deflector 34 can be rotated about 90° in a clockwise direction from the full line to the broken line position of Figure 4 in order to permit the liquid issuing from the tube 28 to flow out of the boss 30, while the yarn or tow continues to run from the end 29 of the tube 28 to the mouth 32 of the tube 31.

The foregoing movement of the deflector 34 is made possible by the disposition and shape of the tube 37 which supplies liquid to the tube 31. The tube 37 enters the box 27 through a rubber sleeve 38 and, near the upper end of tube 37, there is a bend which leads to nozzle 39 which lies within the tube 31, in about the same position as the nozzle 21 in relation to the tube 13. The exact position of the nozzle in the tube can be appreciated by a comparative study of Figures 5 and 6. In Figures 5 and 6 the nozzles 21 and 39, respectively, are shown in section so that their exact position can be particularly appreciated.

In Figure 7 there is shown another type of tube and nozzle arrangement similar to the arrangement of Figures 4 and 6 except that the supply tube instead of entering the treating tube 40 through its mouth 41 passes through a portion of the tube wall. The effect in operation is quite similar to the effect of Figure 6, but an advantage accrues due to the fact that the mouth 41 is unobstructed for easy entrance of the tow.

While Figures 1, 2 and 4 show only the discharge end of one treating tube and the entry end of the next tube in the series, it is to be understood that the deflector and liquid supply arrangements of these figures can be ap-

plied to all of the tubes of a series, whatever number is required to accomplish the desired liquid treatment.

While this invention has been described in respect of the aftertreatment of tow, it is apparent that the disposition of the liquid supply nozzles within the treating tubes is possible in any of the larger size ranges of tubes. The smaller tube sizes are best accommodated by the Figure 7 arrangement where the mouth 41 is unobstructed.

What is claimed is:

10. Tube spinning apparatus comprising yarn and liquid delivery means, a treating tube, said means having an exit end above and horizontally offset from the mouth of said tube, a deflector having a channel therein, and means supporting said deflector for pivotal movement about a vertical axis to and from a position in which its channel defines a path between said exit end and said mouth and a position in which it is out of registry with said exit end.
20. Tube spinning apparatus comprising yarn and liquid delivery means, a treating tube, said means having an exit end above and horizontally offset from the mouth of said tube, a liquid supply tube having a nozzle within said treating tube beyond the mouth thereof, a deflector having a channel therein, and means supporting said deflector for pivotal movement about an axis to and from a position in which its channel defines a path between said exit end and said mouth and a position in which it is out of registry with said exit end.
30. Tube spinning apparatus comprising yarn and liquid delivery means, a treating tube, said means having an exit end above and horizontally offset from the mouth of said tube, a liquid supply tube extending in a path at an angle to said treating tube, said supply tube being curved and having a nozzle near its end aligned with the treating tube, a deflector having a channel therein, and means supporting said deflector for pivotal movement downwardly about an axis to and from a position in which its channel defines a path between said exit end and said mouth and a position in which it is out of registry with said exit end.
40. Tube spinning apparatus comprising yarn and liquid delivery means, a treating tube, said means having an exit end above and horizontally offset from the mouth of said tube, a liquid supply tube defining with said treating tube an angle, said supply tube passing through the wall of said treating tube and terminating in a nozzle extending parallel to the said treating tube, a deflector having a channel therein, and means supporting said deflector for pivotal movement downwardly about an axis to and from a position in which its channel defines a path between said exit end and said mouth and a position in which it is out of registry with said exit end.
50. Tube spinning apparatus comprising yarn and liquid delivery means, a treating tube, said means having an exit end above and horizontally offset from the mouth of said tube, a liquid supply tube extending in a path at an angle to said treating tube, said supply tube being curved and having a nozzle near its end aligned with, and lying within, the treating tube, a deflector having a channel therein, and means supporting said deflector for pivotal movement downwardly in a path intersecting a line, constituting an axial extension of said treating tube, about an axis to and from a position in which its channel defines a path between said exit end and said mouth and a position in which it is out of registry with said exit end.
60. Tube spinning apparatus comprising yarn and liquid delivery means, a treating tube, said means having an exit end above and horizontally offset from the mouth of said tube, a liquid supply tube extending in a path at an angle to said treating tube, said supply tube being curved and having a nozzle near its end aligned with, and lying within, the treating tube, a deflector having a channel therein, and means supporting said deflector for pivotal movement downwardly in a path intersecting a line, constituting an axial extension of said treating tube, about an axis to and from a position in which its channel defines a path between said exit end and said mouth and a position in which it is out of registry with said exit end.
